UNITED STATES PATENT OFFICE.

TERJE AANENSEN FIDJELAND, OF FOSTVEDT, NORWAY.

MAGAZINE FIREARM.

No. 920,363.

Specification of Letters Patent. Patented May 4, 1909.

Application filed October 22, 1908. Serial No. 459,079.

To all whom it may concern:

Be it known that I, TERJE AANENSEN FIDJELAND, gunmaker, citizen of Norway, residing at Fostvedt, Iveland, pr. Christianssand S., Norway, have invented new and useful Improvements in Magazine-Firearms, of which the following is a specification.

My invention relates to magazine fire-arms in which the reloading is effected without the breech-block being turned and the object of the invention is to arrange the breech-block in such a manner that it may at any time be seen from the position of certain outer parts, whether the cock is eased in the mechanism 15 of the fire-arm is cocked or not, and at the same time whether it is barred or not.

A further object of my invention is to provide a trigger device, which is advantageously used in connection with the above mentioned breech-block indicating mechanism. The said device may also be used in every kind of automatic fire-arms and is distinguished by a low number of simple parts which may be easily put together and have 25 a secure co-operation.

The invention is illustrated in the accompanying drawing in which:

Figure 1 is a side view partly in longitudinal section of an uncocked pistol arranged in accordance with my invention. Fig. 2 is a longitudinal section of the rear end of the fire-arm, in cocked, but not secured position. Fig. 3 is an end view of Fig. 2. Figs. 4 and 5 are similar views to Figs. 2 and 3 of the rear parts of the fire-arms in cocked and secured position. Fig. 6 is a front view of the cock indicator. Fig. 7 is a vertical longitudinal section of the breech-block and Fig. 8 a cross section of the same on the line I—I, Fig. 7, 40 shown in the direction of the arrows at the section line. Fig. 9 is a longitudinal section of the breech-block on the line II—II, Fig. 8, shown in the direction of the arrows. Fig. 10 is an end view of Fig. 9, looking to the 45 right. Fig. 11 is a side view of the securing or safety sleeve in inoperative position (corresponding to Figs. 1 to 3). Fig. 12 is a cross section on the line III—III in Fig. 11. Fig. 13 is a cross section on the line IV—IV in 50 Fig. 11. Fig. 14 is a side view of the securing sleeve in operative position (corresponding to Figs. 4 and 5). Fig. 15 is a vertical section through a pistol, showing my improved trigger device. Fig. 16 is a side elevation of the frame with barrel, the several parts of the mechanism being removed.

Figs. 17, 18 and 19 are respectively side view, plan view and front view of the trigger lever. Fig. 20 shows the trigger from beneath partly in section, and Fig. 21 is a side view of 60 the trigger. The Figs. 7—14 and 17—21 are drawn to an enlarged scale.

Referring to Figs. 1—14 of the drawings the breech-block —1— is, in a known manner, fastened in the rear end of a cylindrical 65 casing —3— surrounding the barrel —2—, said casing together with the breech-block moving backward against the pressure of the return spring —4— located between the casing —3— and the barrel —2—, whereby the 70 casing is carried forward by the said spring to the position shown. During this operation the breech-block performs no turning movement. The firing pin —5— is struck by the cock —6— which turns on its pivot 75 —7— and is retained in the cocked position by means of a sear —8— and a nose —9—. The cock is acted on by a spring —10—. The trigger mechanism proper will be described below with reference to the Figs. 80 15—21 of the drawings. The cock —6— plays in an opening —11— made in the underside of the breech-block and as shown the cock is completely inclosed in the fire-arm.

According to the invention there is formed 85 in the rear end of the breech-block a cylindrical chamber —12— open at the rear end in which chamber a rotatable sleeve —13— (Fig. 11) is located. The rear end of this sleeve has a wing —14— and its open front 90 end is formed with a bayonet slot consisting of a lower longitudinal groove —15— and a transverse groove —16— (see Figs. 11, 12 and 14). Near its rear end the sleeve has a transverse groove —17— into which projects the end of a screw —18— and the breech-block, screwed into the rear end of the casing —3—, is locked to the latter by 95 said screw which has a spring lever —19— carrying the sight notch —20—. It should be 100 observed that the combination of the screw —18— locking the breech-block and the spring lever —19— with sight notch —20— forms an important feature of the invention. As the screw —18— passes through holes 105 —21— —22— formed in the rear end of the breech-block (see Figs. 7 and 8) it thereby also serves to retain the safety sleeve —13— in position in the chamber —12—, and at the same time it limits the turning motion of the 110 sleeve, as the groove —17— is of such a length that the sleeve can only turn 90 de-

grees (from the position shown in Figs. 3 and 11 to that shown in Figs. 5 and 14). At its rear end the sleeve is provided with a central hole for the outer end of a movable pin 5 —23—, the so-called "cock indicator", the front end of which is thicker so that it forms a shoulder —24—, provided with a nose —25— projecting downward into the longitudinal groove —15— of the sleeve —13—. 10 The length of the said nose (in the longitudinal direction of the fire-arm) corresponds with the width of the transverse groove —16—.

Between the pin —23— and the sleeve 15 —13— is an annular chamber inclosing a helical spring —26— the front end of which presses against the rear face of the shoulder —24— thereby causing the nose —25— to bear against the rear part of the cock. When 20 the cock is relaxed (Fig. 1) the rear end of the pin —23— is flush with the wing —14—, but when the firearm is cocked the pin will be forced backward against the pressure of the spring so that the rear end of said pin will 25 project beyond the wing —14—, thereby indicating that the firearm is cocked. As the nose —25— is guided along the vertical sides of the opening —11— of the breech-block (see Fig. 8) it is prevented from being 30 turned. In order that the sleeve —13— with the pin —23— may be put into the chamber —12—, the under part of said chamber is provided with a longitudinal groove —27— corresponding with the width and size of the 35 nose —25— (see Figs. 7, 8 and 10). Thus, the nose —25— cannot turn, and as said nose, when the cock is relaxed, projects into the longitudinal groove —15— of the sleeve —13—, it also prevents the sleeve from being 40 turned. When, however, the fire arm is cocked, the nose —25— is opposite the transverse groove —16—, so that the sleeve can now be turned through 90 degrees, the length of the groove —16— being adapted for this 45 turning angle. By the turning of the sleeve the wing —14— is placed horizontally (Fig. 5) and at the same time the nose —28— of the sleeve (see Fig. 14) is caused to bear upon the front face of the cocked cock (Fig. 4) thereby retaining the cock in secured 50 position.

The safety sleeve —13— is held in its two positions by means of a spring —29— (see Fig. 9) which presses against one or the other 55 of the surfaces —30— and —31— on the sleeve (see also Figs. 11 and 13). Said spring —29— plays in a longitudinal groove —32— in the chamber —12— and is made in one piece with the extractor —33— as shown in 60 Fig. 9. At the middle of the extractor is a projection —34— passing through a hole —35— in the breech-block into a notch —36— made in the firing pin —5— thereby holding this pin in position and limiting its 65 movements lengthwise.

From the preceding it will be understood that the wing —14— at any time indicates whether the cock is secured or released, and the pin —23— at the same time shows whether the fire arm is cocked or not. 70

The combination of the parts illustrated is very suitable to the purpose. As will be seen the screw —18— has four functions namely, forming the sight notch, locking the breech-block to the cap, retaining the sleeve —13— and limiting the turning of said sleeve. The extractor —33— has also four functions, namely, forming the extractor itself, holding the firing pin in position, limiting the movements of the said pin and holding the sleeve 80 —13— in its two positions by means of the spring —29—.

I now shall describe the trigger mechanism by reference to Figs. 15-21 of the drawings. As mentioned above the cock is retained in 85 cocked position by means of a sear —8—. This latter preferably constitutes one arm of a pivoted bell crank lever, the other arm —37— of which is acted on by the trigger —38—. The lever —8, 37— is by means of 90 its middle cylindrical portion —39— inserted from the side into a hole —40— (see Fig. 16) in the frame or grip —41— or another fixed part of the frame. The sear —8— plays in the groove or space —42— and normally 95 projects until beneath the cocking nose —9— of the cock —6— as shown in Fig. —15—. The arm —37— has a small thickness and is located nearly horizontally at the side of the frame and is provided with a spring —43—, 100 the free end of which engages a face —44— on the frame and thereby constantly tends to hold the lever —8, 37— in operative position. Normally the arm —37— is locked by a nose —45— arranged on the upper end 105 of an arm —48— pivoted on the pin —47— and pressed by a spring —46— in the position shown, whereby the nose —45— is located directly beneath a lateral projection —49— on the arm —37—. The nose —45— 110 and the projection —49— travel in an opening —50— (see Fig. 16). The upper edge of the arm —37— is provided with an inclined projection —51— located in the path of an oscillatory tooth —52— on the rectilinearly 115 moved trigger —38—. The operative part of the latter is guided on one side by the arm —37— at —53— (see Fig. 17) and on the other side by two faces —54, 55— (see Fig. 16) on the frame. The trigger handle —56— 120 travels in a recess —57— in the rear portion of the trigger bow —58— and is rearwardly provided with a bore, inclosing a spring —59— on a pin —60—. One end of the spring engages the wall of the recess —57— 125 at —61— (see Fig. 16), so that its other end through the spring —59— constantly tends to hold the trigger forward in the position shown in Fig. 15, *i. e.* with the tooth —52— in front of the projection —51—. The 130

tooth — 52 — oscillates about the pin — 62 — and is pressed in the direction of the arrow — 63 — by a spring — 64 —, arranged in a longitudinal groove — 65 —, so that the back 5 of the tooth is stopped by the face — 66 —. The tooth may be turned oppositely the arrow into a notch — 67 — in the under edge of the trigger. When the trigger — 38 — by the finger is carried backward, the tooth — 10 — 52 — meets with the projection — 51 — and tends then to press the latter down which is prevented, however, by the nose — 45 — which is located directly beneath the projection — 49 — of the arm — 37 —. The cocked 15 tooth is therefore locked and the trigger cannot be pulled, before the nose — 49 — by a pressure on the arm — 48 — is moved backward out of the path of the projection — 49 —. As soon as this has taken place the 20 tooth — 52 — acting on the inclined front face of the projection — 51 — will press the latter and the arm — 37 — down, so that the lever — 8, 37 — is turned in a counter clockwise direction about the cylindrical portion 25 — 39 —, and the upper end of sear — 8 — releases the nose — 9 — of the cock — 6 —, whereby the latter under the influence of the spring — 10 — turns upward about the bolt 30 — 7 — and by its blow on the firing pin — 5 — fires the cartridge — 68 —. Immediately thereafter the tooth — 52 — slides over the top of the projection — 51 — and by means of the spring — 43 — the lever — 8, 37 — snaps back in locking position, ready for again 35 holding the cock as soon as the same during the automatic reloading again swings back into cocked position. The trigger still is in its rear position i. e. the tooth — 52 — is behind the top of the projection — 51 — and the 40 spring — 59 — is compressed. When now the handle — 56 — is released the spring — 59 — again carries the trigger — 38 — forward, whereby the tooth — 52 — turning oppositely the arrow — 63 — into the notch 45 — 67 — slides over the projection — 51 — and then snaps back in front of the same. The several parts now again take up the initial position shown.

It is obvious that the described trigger 50 mechanism, which comprises only the parts — 38 and 37, 8 —, may be used in connection with any automatic fire-arm independent of the manner in which the reloading takes place and of the special mechanism therefor 55 and also independent of the special arrangement of the cock. So it is not necessary that the cock is turnable on a bolt but it can also be longitudinally movable or as in many existing automatic fire-arms the cock may form 60 a nose on the breech-block &c. The described trigger mechanism easily may be modified to suit the several constructions, as only the shape and position of the sear — 8 — is altered according to the existing arrangements. Finally it is understood that the 65

tooth — 52 — may be attached to the arm — 37 — and the projection — 51 — be arranged on the trigger — 38 —.

Having now described my invention what I claim as new and desire to secure by Letters 70 Patent is:

1. A fire arm comprising a non-revolving breech block having a slot therein, a trigger, a cock operated by said trigger and extending through the slot, a firing pin within the 75 breech block adapted to be engaged by the cock, a safety sleeve in the rear end of the breech block, an exterior handle 14 on said sleeve, said sleeve having a bayonet slot in its inner end, a pin in said sleeve having a 80 projection on its inner end adapted to engage with the bayonet slot in the sleeve and to abut against the cock, and a spring for normally holding said projection against the 85 cock.

2. A fire arm comprising a non-revolving breech block having a slot therein, a cock projecting through said slot, a firing pin within the breech block operated by said cock, a safety sleeve in the rear end of said 90 breech block having a bayonet slot in its inner end and an exterior wing on its rear end, a pin within said sleeve having a nose on its inner end engaging with the bayonet slot, a spring for pressing the nose against the 95 cock, the rear end of said pin projecting from the rear end of the sleeve when the arm is cocked and being flush with the rear end of the sleeve when the cock is released, said breech block having a groove therein into 100 which the nose projects, so as to prevent the sleeve from being turned as long as the arm is not cocked, said nose being opposite the transverse portion of the bayonet slot when the arm is cocked so that the sleeve can be 105 turned, whereby a portion of the sleeve engages the cock and secures the same in cocked position.

3. In a fire arm the combination with a breech block, a safety sleeve in the rear end 110 of said block, an exterior transverse groove in said sleeve, and a pin in the breech block having its end projecting into said groove whereby said groove is retained in the block and has a limited turning movement therein. 115

4. In a fire arm the combination with a breech block, a safety sleeve in the rear end thereof, said sleeve having a limited turning movement within the block and provided with two flat portions adjacent one end, an 120 extractor, and a spring carried by said extractor engaging with one or the other of said flat portions to hold the sleeve against turning.

5. In a fire arm, the combination of a 125 breech block, a frame, a barrel secured to the front end of the frame, a casing surrounding said barrel and frame, a screw securing the casing to the breech block, and a spring lever forming an extension of the 130

head of said screw and having, on its end, a sight notch.

6. In a fire arm the combination with a cock, a bell crank lever having its vertical arm engaging the cock, a spring for holding the bell crank lever normally in position to engage the cock, an inclined portion on the horizontal part of the bell crank lever, a horizontally movable portion, a tooth on said portion adapted to contact with the inclined portion to rock the bell crank lever and release the cock, means for moving said tooth carrying portion by the finger, a spring for returning said portion to its normal position, and means for permitting the tooth to move out of the range of the inclined portion when the tooth carrying portion returns to its normal position.

7. In a fire arm the combination with a cock, and means for operating the same, comprising an oscillating bell crank lever, a frame having a lateral recess in which the upper arm or sear of said bell crank lever sets, and the horizontal portion 37 of said lever having a guiding point 53 thereon, a trigger 38 having its inner end sliding on said guiding point, and its other end guided on the frame, a cylindrical portion 39 forming the connection between the two arms of the bell crank, said cylindrical portion forming a turning pin for the bell crank lever, and the frame having side holes 40 therein

in which the ends of the cylindrical portion bear.

8. In a fire arm the combination with a 35 cock, an oscillating bell crank lever for releasing the cock, a projection 49 on the releasing portion 37 of the said bell crank lever, a spring actuated arm on the handle portion of the arm, a safety nose 45 on said 40 arm adapted to engage with the said projection 49 to prevent movement of the bell crank lever.

9. In a fire arm the combination of a 45 cock, a bell crank lever for releasing the 45 cock, an inclined portion 51 on the horizontal portion 37 of said bell crank lever, a trigger having a horizontally movable portion, a movable tooth carried by the said portion and adapted to engage with the said 50 inclined portion 51 to oscillate the bell crank lever, the face 66 on said horizontally movable portion being adapted to engage the tooth to prevent movement thereof in one direction, and a spring allowing yielding 55 movement of the tooth in the other direction.

In testimony whereof I have signed my name to this specification in the presence of two subscribing witnesses.
